UNITED STATES PATENT OFFICE.

CHRISTOPHER FLINN, OF ALLEGHENY, PENNSYLVANIA, ASSIGNOR TO
PRESSED STEEL CAR COMPANY, OF PITTSBURG, PENNSYLVANIA, A
CORPORATION OF NEW JERSEY.

CONVEYER.

No. 800,095.

Specification of Letters Patent.

Patented Sept. 19, 1905.

Application filed June 20, 1904. Serial No. 213,240.

To all whom it may concern:

Be it known that I, CHRISTOPHER FLINN, of 5
Allegheny, Allegheny county, Pennsylvania,
have invented a new and useful Conveyer, of
which the following is a full, clear, and exact
description, reference being had to the ac-
companying drawings, forming part of this
specification, in which—

Figure 1 is a side elevation, partly in sec- 10
tion, showing a portion of my improved con-
veyer. Fig. 2 is a cross-section on the line II
II of Fig. 1. Figs. 3 and 4 are detail views
of the eccentrics which I employ. Fig. 5 is a
view showing the driving mechanism for the
main shaft. Fig. 6 shows a modification, and
Fig. 7 is a plan view of the same on a larger
scale.

The purpose of my invention is to provide
means for conveying metal from one part of
a mill to another. It is especially adapted to
convey hot pieces of metal and simultaneously
cool them in their passage.

The mechanism is characterized by sim- 25
plicity of construction and economy in main-
tenance and operation, which are of great im-
portance in a machine of this kind.

The drawings show the preferable construc-
tion of the apparatus; but those skilled in the
art will be able to modify it in various ways.

30 The conveyer comprises a series of fixed
rails 2, set parallel to each other and consti-
tuting a cooling-bed and conveying-table.
They are supported upon suitable posts or
standards 3, to which they are fastened by
35 clamps 4 to assure rigidity of construction.
The moving mechanism consists of rails or
beams 5, which are set in the spaces between
the fixed rails 2 and are preferably connected
by cross-bars 6, which cause them to move in
40 unison. These moving beams are supported
by boxes 7, which inclose eccentrics 8, forming
part of transverse shafts 9, driven simulta-
neously by gearing 10 from a main shaft 11.
The rotation of the eccentrics 8 by the shafts
45 9 imparts a rotative motion to the moving
beams 5, causing them to alternately rise and
lower, and in the part of their motion which
is above the stationary rails 2 they move for-
ward in a circular arc, the radius of which is
50 the distance from the centers of the eccen-
trics to the axis of the shafts 9. Therefore
any articles which are placed upon the rails 2

will be engaged by the moving beams 5 and
will be moved forward step by step, being
raised from the fixed rails, carried forward, 55
and then deposited thereon while the moving
rails are describing the upper half of their
circular movement and resting on the fixed
rails while the moving beams are describing
the lower half of their circular movement in 60
a backward direction. The length of each
step thus imparted to the articles by the mov-
ing beams is determined by the throw of the
eccentrics, and the rapidity of the motion is
determined by the speed of the driving-gear- 65
ing.

The moving beams are provided with wear-
ing-pieces 12, preferably of cast-iron, which
afford transverse openings 13 for the passage
of air, so that the beams themselves are pre- 70
vented from being overheated by hot articles
which are being carried.

In Fig. 5 I show means for driving the main
shaft 11, consisting of a worm-wheel 14 and
worm 15, which is rotated by a suitable mo- 75
tor 16 or some other power connection.

In Figs. 3 and 4 I show means by which the
throw of the eccentrics can be varied to suit
the requirements of the particular use to which
the conveyer is put. Each eccentric consists 80
of a disk 8, having an elongated slot 17 fit-
ting on a squared portion 9' of the shaft 9.
The slot is longer than the cross-section of the
shaft and affords room for the interposition
of liners 18. By changing the position of one 85
or more of the liners from one side of the
shaft to the other the degree of eccentricity
may be varied. The eccentric is held on the
shaft and the shaft held in contact with the
liners by a set-screw 19, set in a countersunk 90
recess in the eccentric, as shown in Fig. 4.

In Fig. 6 I show a modification of the ap-
paratus in which the fixed and stationary rails
are set on an incline, and for the purpose of
preventing the material conveyed thereby 95
from slipping back stops 20 can be placed on
the stationary rails and on the moving beams
to constitute bearings for the material as it is
deposited thereon.

I claim—

1. A conveyer comprising a series of fixed
supports for the material to be conveyed, a set
of moving beams and rotary eccentrics sup-
porting the moving beams and arranged to

impart thereto an upward motion and a forward motion above the fixed supports; substantially as described.

2. A conveyer comprising a series of fixed supports for the material to be conveyed, a set of moving beams, rotary eccentrics supporting the moving beams and arranged to impart thereto an upward motion and a forward motion above the fixed supports, a shaft 11 extending parallel with the moving beams, and gearing connecting the eccentrics therewith; substantially as described.
3. A conveyer comprising a series of fixed supports, a set of moving beams, rotary eccentrics supporting the moving beams and arranged to impart thereto an upward motion and a forward motion above the fixed support, and means for varying the throw of the eccentrics; substantially as described.
4. A conveyer comprising a series of fixed

supports set in the same plane, and a set of parallel moving beams mounted on eccentrics and adapted to have a rotary motion extending above and below the level of the fixed supports, said moving beams having facings 25 provided with air-passages; substantially as described.

5. A conveyer comprising a series of fixed supports set in the same plane, and a set of moving parallel beams mounted on eccentrics 30 and adapted to have a rotary motion extending above and below the level of the fixed supports, said eccentrics being adjustable in throw; substantially as described.

In testimony whereof I have hereunto set 35 my hand.

CHRISTOPHER FLINN.
